UNITED STATES PATENT OFFICE.

ELAM A. GROSS, OF CAMDEN, NEW JERSEY.

DESIGN FOR A NEWSPAPER AND LETTER HOLDER.

SPECIFICATION forming part of Design No. 33,241, dated September 25, 1900.

Application filed August 30, 1900. Serial No. 28,610. Term of patent 14 years.

To all whom it may concern:

Be it known that I, ELAM A. GROSS, a citizen of the United States, residing at Camden, in the county of Camden and State of New Jersey, have produced a new and original Design for a Newspaper and Letter Holder, of which the following is a specification.

This invention relates to a design for a newspaper and letter holder, and the leading feature thereof resides in the design forming the subject-matter of the accompanying illustration, wherein—

Figure 1 is a perspective view of a holder embodying the features of the design. Fig. 2 is a side elevation of the same.

The design is characterized by a rectangular body open at one end and composed of a lower horizontal bar 1 continuous with vertical bars 2 parallel to each other and at their

upper ends having inwardly-extending semi-circular bends 3, merging into depending legs 4, with lower right-angular outwardly-projecting terminals 5. On the ends of the said latter parts are eyes 6, and, as shown by Fig. 2, the entire device has a normal outwardly-inclined position to a vertical plane.

Having thus described the invention, what is claimed as new is—

The design for a newspaper and letter holder, herein shown and described.

In testimony that I claim the foregoing as my own I have hereto affixed my signature in the presence of two witnesses.

ELAM A. GROSS.

Witnesses:

JOS. W. NEWELL,
SAMUEL F. SMITH.
